 Associated Electric Laboratories, Inc., Chicago,
 Ill., a corporation of Delaware

Application March 14, 1938, Serial No. 195,812

25 Claims. (Cl. 179—81)

The present invention relates to substation apparatus and has for one of its objects the provision of an improved arrangement for incorporating an auxiliary loud speaking sound reproducing unit in the telephone substation circuit.

5 A substation of the character mentioned conventionally comprises a telephone transmitter and receiver, a hook or cradle switch, a ringing device, and an auxiliary loud speaking sound reproducing unit arranged for alternative use with the telephone receiver. When the substation is to be used in a system of the automatic type, there is also included in the circuit thereof a dial operated impulsing device for transmitting switch 10 control impulses over the associated line to the line terminating exchange. In this type of substation circuit it is desirable to provide apparatus for preventing operation of the transmitter from effecting operation of the receiver when the receiver is connected for use, and for preventing operation of the transmitter from effecting operation of the auxiliary sound reproducing unit when this unit is connected for use. It is also desirable to provide circuit apparatus so arranged 15 that voltage or current transients occasioned by operation of the impulsing device are not transmitted to the receiver or the auxiliary sound reproducing unit for reproduction. Various arrangements have in the past been utilized for 20 accomplishing these purposes and while, for the most part, these prior arrangements are perfectly satisfactory in operation, they are, in the usual instance, rather complicated in character, and expensive. For example, it has been more or less 25 conventional practice to provide separate circuits associated respectively with the receiver and the auxiliary sound reproducing unit for preventing voice frequency energy generated by operation of the transmitter from being delivered to the receiver and the auxiliary sound reproducing unit 30 for reproduction.

It is an object of the present invention to provide a telephone substation circuit which is equipped to provide amplified reproduction of 35 audio frequency currents transmitted to the substation, and which is of simple and economical arrangement and requires a minimum amount of circuit equipment.

It is a further object of the invention to provide 40 in a substation circuit of the character mentioned an improved arrangement for preventing transient voltages or currents occasioned by operation of the impulsing device from being reproduced as clicks by the auxiliary sound reproducing unit.

45 It is a still further and more specific object of

the invention to provide in a substation circuit of the character described apparatus whereby the same anti-side tone impedance network may be utilized to prevent sound transmitted to the transmitter from being reproduced by the substation receiver or by the auxiliary sound reproducing unit.

In the illustrated embodiment of the invention, the substation circuit is shown as comprising a transmitter, a receiver and an anti-side impedance network arranged to be interconnected to form a substation circuit. The anti-side tone impedance network is, when the receiver is connected in the substation circuit, operative to prevent audio frequency energy generated by the operation of the transmitter from being delivered to the receiver. Also included in the substation is an auxiliary sound reproducing device and switching means comprising the usual receiver-operated hook switch, for substituting this auxiliary sound reproducing unit for the receiver in the substation circuit. In accordance with one feature of the invention, the switching means, the anti-side tone impedance network, and the sound reproducing unit are so connected and arranged that the anti-side tone impedance network is also operative to prevent audio frequency energy generated by the operation of the transmitter from being delivered to the auxiliary sound reproducing unit when this unit is operatively included in the circuit. The auxiliary sound reproducing unit comprises a vacuum tube amplifier and a loud speaker or translating device connected in tandem in the order named, and there is included in the amplifier input circuit the secondary winding of a voltage amplifying coupling transformer. The substation is equipped for automatic service, a dial controlled impulsing device being provided for transmitting switch control impulses by way of the associated line to the line terminating exchange. In accordance with a further feature of the invention, there is provided an arrangement for effectively short-circuiting the secondary winding of the coupling transformer during the operation of the impulsing device, thereby to prevent voltage transients occasioned by operation of the device from being amplified by the vacuum tube amplifier and delivered to the loud speaker.

The novel features believed to be characteristic of the invention are set forth with particularity in the appended claims. The invention, both as to organization and method of operation, together with further objects and advantages thereof, will best be understood by reference to the specification, taken in connection

with the accompanying drawing, in which there is illustrated in partially schematic form an automatic telephone system having incorporated therein a substation connected and arranged in accordance with the present invention.

Referring now to the single figure of the drawing, there is diagrammatically illustrated a telephone system comprising an automatic telephone exchange 10 which may, if desired, constitute a private automatic branch exchange. Terminating at the exchange 10 are a plurality of telephone lines, two of which are indicated at 11 and 12. The ends of the lines remote from the exchange 10 terminate in substations of the automatic type, that associated with the line 11 being diagrammatically illustrated at A and that associated with the line 12 being indicated generally at B. The automatic exchange 10 comprises the usual subscriber controlled automatic switches for setting up connections between the telephone lines of the system. More particularly, these switches are, in accordance with conventional practice, divided into two classes, namely, non-numerical switches such, for example, as line finder or line switches; and numerical switches, such, for example, as selector and connector switches, which respond to impulses transmitted thereto over calling ones of the telephone lines and function to perform the usual line group, subgroup and unit selecting operations. The connector switches at which the lines terminate are, in accordance with conventional practice, equipped to perform the usual auxiliary functions of: testing a selected called line to determine the idle or busy condition thereof, returning busy tone over the calling line in the event a selected called line is found busy, and projecting ringing current over a selected called line to actuate the signal device at the called 35 substation in the event a selected called line is idle at the time it is tested.

Referring now more particularly to the equipment provided at the substation B, this substation comprises switching means in the form of a call-and-answer key 13 for connecting the substation apparatus to the line 12, a ringing or signal device 14 connected across the line conductors 16 and 17 in series with a condenser 15; a transmitter 18, a receiver 19, a dial controlled 40 impulsive device 20, and switching means in the form of a hook or cradle switch 21. The switch 21 comprises a member 22 for supporting the receiver 19 when not in use, and switch springs 23 to 27, inclusive, which are operative, in response to the removal of the receiver 19 from the supporting member 22, to include the receiver 19 in the substation circuit. The impulsive device 20 is of the conventional dial operated type and comprises a pair of impulsive 45 springs 28 and two sets of shunt contact springs 29 and 30. The springs 29 and the springs 30 are normally restrained to the open circuit positions indicated in the drawing, and are so arranged that the dial mechanism closes the same during operation of the impulsive device. Also included in the substation equipment is an auxiliary sound reproducing unit comprising a vacuum tube amplifier 31 and a translating device or loud speaker 32. The amplifier 31 is provided with an input circuit which includes the secondary winding 33 of a voltage step-up or amplifying transformer 34, which transformer is more generally designated as a coupling element. The transformer 34 also includes a primary winding 35 which is normally connected across

one element 36 of an anti-side tone impedance network indicated generally at 37. This network, which is provided for the purpose of preventing audio frequency energy generated by operation of the transmitter 18 from being delivered to the receiver 19 or to the input circuit of the amplifier 31, further comprises a second inductance element 38 connected in series with the element 36. Both of the elements 36 and 38 are coupled to a third inductance element 39. Also included in the network 37 is a resistor 40 which is provided for the purpose of balancing the resistive impedance of the line 12 and other impedances necessarily connected to this line when the substation B is included in an established 15 telephone connection.

For the purpose of minimizing acoustical coupling between the transmitter 18 and the auxiliary sound reproducing unit, it is contemplated that these elements of the circuit shall be remotely located with respect to each other. More particularly, the auxiliary sound reproducing unit is remotely located with respect to the remainder of the substation apparatus and is connected thereto by means of a cable 42 comprising conductors 43 to 46, inclusive, which are preferably formed of tinsel wire, permitting continuous handling of the cable 42 with a minimum likelihood of breaking the enumerated conductors.

In order to prevent voltage transients occasioned by operation of the impulsive device 20 from being reproduced as clicks by the receiver 19 or the auxiliary sound reproducing unit, the contact springs 29 are arranged to complete a path for at least partially short-circuiting the primary winding 35 of the transformer 34 when the hook switch 21 occupies the position shown in the drawing, and for short-circuiting the receiver 19 when this receiver is removed from its supporting member 22 to permit the switch 21 to assume its off-normal position. As a further expedient for preventing such transient voltages from being reproduced by the auxiliary sound reproducing device, there is provided a path for effectively short-circuiting the input circuit or, more particularly, the secondary winding 33 of the transformer 34 for such voltages during operation of the impulsive device 20. This path, which is normally open, comprises a 50 capacitance element 47 of large capacity and is arranged to be completed in response to the operation of the impulsive device 20 through closure of the shunt contact springs 30. In order to prevent local electrical disturbances picked up by the line 12 from being reproduced by the auxiliary sound reproducing unit when this unit is conditioned for operation, the key or switch 13 is equipped with springs for disconnecting the substation circuit from its associated line 12 when the substation apparatus is not in use. The contact springs 48 and 49 of the key 13 are also arranged to complete the path comprising the capacitance element 47 for effectively short-circuiting the secondary winding 33 of the transformer 34 when the substation apparatus is disconnected from the line 12.

As indicated in the drawing, the substation B is of the local battery type, a battery 56 being provided for producing voice frequency currents in response to the operation of the transmitter 18 when this transmitter, the inductance element 39, and the battery 56 are connected, through operation of the key 13 to its off-normal position, to form a closed transmitting loop.

In order to give a visual indication that the substation B is connected to its associated line 12, or that the key 13 is operated to its off-normal position, there is provided a signal lamp 57 which is arranged to be energized when the contacts 54 and 55 of the key 13 are closed. Referring now to the operation of the system, and assuming, for example, that a call is initiated at the substation A and routed by way of the automatic switching equipment provided in the exchange 10 and the line 12 to the substation B at a time when the last-mentioned substation is idle, when the line 12 is seized by one of the connector switches provided in the exchange 10 and tests idle, ringing current is projected over the line to actuate the ringing device 14, thereby to give an audible indication that the substation B is being called. The call is answered by operating the key 13 to its off-normal position, thereby to interrupt, at the springs 48 and 49, the above-mentioned path for effectively short-circuiting the secondary winding 33 of the transformer 34, and to complete, at the springs 54 and 55, the above-mentioned transmitting loop including the transmitter 18, the battery 56, and the inductance element 39. When the key 13 is operated to its off-normal position, an obvious circuit is completed at the springs 54 and 55 for energizing the signal lamp 57, and a direct current bridge is placed across the line conductors 16 and 17 of the line 12. This bridge may be traced from the conductor 16 by way of the springs 50, 51 and 28, the resistor 40, the inductance elements 36 and 38, and the switch springs 52 and 53 to the opposite line conductor 17. The completion of this bridge results in the operation of the connector switch to arrest the ringing operation and to complete a talking connection between the calling and called substations in the usual manner.

The answering party has the option of employing the receiver 19 or the auxiliary sound reproducing unit for translating incoming audio frequency currents into sound energy. If the answering party elects to employ the receiver 19 for this purpose, this receiver is removed from its supporting member 22 in the usual manner. The hook switch 21 responds to this operation by opening its contact springs 26 and 27, closing its springs 23 and 24, and closing its springs 25 and 26. Following the operation of the hook switch 21 to its off-normal position, the receiver 19 is conditioned to reproduce incoming audio frequency currents as sound energy, and the transmitter 18 is conditioned to convert sound energy into corresponding audio frequency currents for transmission over the line 12 to the calling substation A. Specifically, the path traversed by incoming voice frequency currents extends from the line conductor 16, by way of the switch springs 50 and 51, the impulsing springs 28, the receiver 19, the switch springs 26 and 25, the inductance element 38 of the anti-side tone impedance network 37, and the switch springs 52 and 53, to the opposite line conductor 17. When sound waves impinge upon the diaphragm of the transmitter 18, undulating audio frequency currents corresponding to the sound waves are set up in and circulate through the closed loop circuit comprising the transmitter 18, the inductance element 39 and the battery 56. The alternating component of this current causes an induced voltage of corresponding character to be developed across the terminals of the series connected inductance elements 36 and 38. This

induced voltage causes audio frequency current to be projected over the line 12, through the switch train in the exchange 10, and over the line 13 to the receiver at the calling substation A. The path of this current may be partially traced as extending by way of the line conductor 17, the switch springs 53 and 52, and the inductance element 38 where it divides, one branch extending by way of the impedance element 36, the resistor 40, the impulsing springs 28, and the springs 51 and 50 to the opposite line conductor 16; and the other branch extending by way of the springs 25 and 26, the receiver 19, the impulsing springs 23, and the springs 51 and 50 to the opposite line conductor 16. Due to the voltage induced in the inductance element 38, a circulating current is set up in the closed circuit comprising this element, the resistor 40, the receiver 19, and the switch springs 25 and 26. By proportioning the turns of the two elements 36 and 38 so that the voltage developed across the inductance element 38 bears the correct relation to that developed across the inductance element 38, the circulating current noted can be made equal and opposite to that flowing through the receiver 19 as a consequence of the voltage induced in the inductance element 38. Thus, the current flowing through the receiver 19 during operation of the transmitter 18 may be reduced substantially to zero, so that the well-known anti-side tone effect is realized.

In the event the answering party elects to employ the auxiliary sound reproducing unit as the receiving means, the amplifier on-off switch, not shown, is operated to condition the amplifier 31 for operation, and the receiver 19 is not removed from its supporting member 22. With the hook switch 21 in its normal position as indicated in the drawing, and with the answer key 13 operated to its off-normal position, the primary winding 35 is substituted for the receiver 19 in the substation circuit. More particularly, the path of the signal currents incoming to the substation B may be partially traced as extending by way of the line conductor 17, the switch springs 53 and 52, the inductance element 38, the cable conductor 44, the primary winding 35, the cable conductor 43, the switch springs 26 and 27, the impulsing springs 28, and the switch springs 51 and 50 to the opposite line conductor 16. Since the primary winding 35 is literally substituted for the receiver 19 in the substation circuit, it will be understood that the anti-side tone impedance network 37 functions to prevent voice frequency energy generated by operation of the transmitter 18 from being delivered to and reproduced by the auxiliary sound reproducing unit. On the other hand, incoming audio frequency currents traversing the primary winding 35 over the circuit just traced are amplified by the amplifier 31 and delivered to the loud speaker 32 for reproduction. The path of audio frequency currents generated by operation of the transmitter 18 is substantially the same as that traced above for the case when the receiver 19 is included in the circuit.

When the conversation is terminated and the connection is released, the key 13 is restored to its normal position to recomplete, at the springs 48 and 49, the above-mentioned path for effectively short-circuiting the secondary winding 33 of the transformer 34. If the answering party fails to restore the key 13, the energized condition of the lamp 57 is a visual reminder that the substation B is still connected to the line 75.

12. Obviously, when the key 13 is restored to normal, the circuit for energizing this lamp and the closed transmitting loop are interrupted at the springs 54 and 55. If the auxiliary sound reproducing unit utilized as the receiving means, the amplifier 31 is deenergized when the on-off switch associated therewith is restored to its off position. On the other hand, if the receiver 19 is utilized as a receiving means, this receiver is restored to its supporting member 22, in the usual manner, to return the hook switch 21 to its normal position. It will be apparent from the foregoing description that the auxiliary sound reproducing unit and the receiver 19 may alternately be used as the receiving means during a single conversation by the simple expedient of restoring or removing the receiver 19 from its supporting member 22, thereby to actuate the hook switch 21 between its two operating positions.

In order to initiate a call at the substation B intended for one of the other automatic substations, such, for example, as the substation A, the calling party first actuates the call and answer key 13 to its off-normal position to perform the functions described above; and then actuates the impulsing device 29 in accordance with the directory number designating the called substation. It will be noted that, when the key 13 is operated to its off-normal position, the direct current bridge, traced above, is connected across the line conductors 16 and 17 and the line 12, thereby to cause an associated or assigned non-numerical switch in the exchange 10 to respond in the usual manner. During operation of the impulsing device 29, the impulsing springs 28 are alternately opened and closed in the usual manner, thereby to transmit impulses by way of the line 12 to the automatic switching equipment in the exchange 10. This equipment responds to the impulses in the usual manner to cause the connection to be routed by way thereof to the called line 11. During each operation of the impulsing device 29 or, more particularly, during each digit dialed at the substation B, the shunt springs 29 and the shunt springs 30 are closed. At the springs 29 a path is completed for excluding the primary winding 35, the resistor 40 and the inductance element 36 from the impulsing circuit. Thus, when the springs 29 are closed, and with the hook switch 21 in its normal position as indicated in the drawing, the primary winding 35 is short-circuited over a short-circuiting path extending from its upper terminal by way of the cable conductor 43, the switch springs 25 and 27, the shunt springs 29, and the cable conductor 44 to the lower terminal of the winding 35. The completion of this path effectively reduces the possibility of transient voltages occasioned by operation of the impulsing device from being impressed on the input circuit of the amplifier 31. There may be, however, a certain amount of inductive, capacitive or resistive coupling between the cable 42 and the other circuit elements, such that small transient voltages are developed across the terminals of the winding 35 during operation of the impulsing device. When amplified by the transformer 34 and the amplifier 31, these small voltages may produce objectionable noise in the form of clicks reproduced by the loud speaker 32. In order to obviate this possibility, the shunt springs 30 are arranged to complete the above-mentioned path for effectively short-circuiting the input circuit to the amplifier 31 or, more particularly the sec-

ondary winding 33 of the transformer 34 for transient or alternating voltages during operation of the impulsing device 29. This last-mentioned short-circuiting path extends from the upper terminal of the winding 33 by way of the capacitor 47, the cable conductor 46, the shunt springs 30 and the cable conductor 45 to the lower terminal of the transformer winding 33. The capacitance value of the capacitance element 47 is chosen of a large value so that the impedance of the above-traced path to transient or low frequency audio currents is substantially zero, and thus, even though substantial currents are developed in the secondary winding 33 during operation of the impulsing device 29, the potential difference between the terminals of this winding is held at an exceedingly low value.

When the operation of the impulsing device 29 is ended, the shunt springs 29 and 30 are opened, in the usual manner, to interrupt the above-traced short-circuiting paths, and thereby to condition the substation circuit for voice frequency current transmission and reception. In this connection it will be apparent that, if the selected called line 11 is tested and found busy, 25 busy tone current is returned over the calling loop circuit to traverse the primary winding 35 of the auxiliary sound reproducing unit and, as a consequence, is reproduced by the loud speaker 32 to indicate that the desired connection cannot immediately be obtained. If, on the other hand, the called line is idle and ringing current is projected thereover to signal the called substation, ring-back tone current is conducted back over the calling line and through the primary winding 35 of the transformer 34 to energize the auxiliary sound reproducing unit and thus indicate that the called substation is being rung. When the called subscriber answers the call, the desired conversational connection is 40 completed in the usual manner.

In view of the foregoing description, it will be apparent that the receiver 19 may be utilized by the calling party as the receiving means and, further, that this receiver may be removed from its supporting member 22 either before or after the dialing operation is performed. If the receiver is removed from its supporting member before the impulsing device is actuated, the shunt springs 29 serve to short-circuit the receiver in an obvious manner. Also, with the receiver removed from its supporting member, the above-traced path for short-circuiting the winding 33 of the transformer 34 is completed at the springs 23 and 24 of the hook switch 21 55 independently of the shunt springs 26, and is held completed so long as the receiver 19 is withheld from its supporting member. As a consequence of this arrangement, the auxiliary sound reproducing unit is substantially prevented from 60 reproducing any audio frequency energy incidentally picked up by virtue of stray coupling between its input circuit and the other elements of the substation circuit, even though it is conditioned for operation. Further to preclude the 65 possibility of voice frequency currents being delivered to the auxiliary sound reproducing unit when the receiver 19 is operatively included in the substation circuit, the circuit for energizing the primary winding 35 of the transformer 34 70 is held open at the springs 26 and 27 of the hook switch 21. In this case, as well as in the case where the substation B is the called substation, the receiver 19 and the auxiliary sound reproducing unit may be interchanged at will 75

in the substation circuit through the simple expedient of operating the hook switch 21 between its two operating positions.

In order to release the connection as established in the above-described manner after the conversation is terminated, it is only necessary for the calling party to actuate the key 13 to its normal position to interrupt the loop circuit extending to the operated switch train in the exchange 10. When the key 13 is restored to normal the other functions enumerated above are performed, that is, the transmitting loop is interrupted, the lamp 57 is deenergized, and the above-traced path for effectively short-circuiting the winding 33 of the transformer 34 is completed. When the calling loop circuit is interrupted through the operation of the key 13 to its normal position, the operated switch train is released in the usual manner. Obviously, if the receiver 19 is used as the sound reproducing device, this element is restored to its supporting member 22 at the end of the conversation. On the other hand, if the auxiliary sound reproducing unit is utilized, this unit is deenergized by returning the on-off switch to its off position.

While there has been described what is at present considered to be the preferred embodiment of the invention, it will be understood that various modifications may be made therein, and it is intended in the appended claims to cover all such modifications as fall within the true spirit and scope of the invention.

What is claimed is:

1. A telephone substation adapted to be connected to a telephone line for conversation over said line and comprising, in combination, a transmitter, a receiver and an anti-side tone impedance network arranged to be interconnected to form a substation circuit, said anti-side tone impedance network being operative to prevent audio frequency energy generated by operation of said transmitter from being delivered to said receiver, an auxiliary sound reproducing device, and switching means for substituting said auxiliary sound reproducing unit for said receiver in said substation circuit, said switching means, said network and said auxiliary sound reproducing unit being so connected and arranged that said network is operative to prevent audio frequency energy generated by operation of said transmitter from being delivered to said auxiliary sound reproducing unit when said auxiliary sound reproducing unit is operatively included in said substation circuit.
2. A telephone substation adapted to be connected to a telephone line for conversation over said line and comprising, in combination, a transmitter, a receiver and an anti-side tone impedance network arranged to be interconnected to form a substation circuit, said anti-side tone impedance network being operative to prevent audio frequency energy generated by operation of said transmitter from being delivered to said receiver, an auxiliary sound reproducing unit including an amplifier and a loud speaker connected in tandem in the order named, and switching means for substituting said auxiliary sound reproducing unit for said receiver in said substation circuit, said switching means, said network and said amplifier being so connected and arranged that said network is operative to prevent audio frequency energy generated by operation of said transmitter from being delivered to said amplifier when said amplifier is operatively included in said substation circuit.

3. A telephone substation adapted to be connected to a telephone line for conversation over said line and comprising, in combination, a transmitter, a receiver and an anti-side tone impedance network arranged to be interconnected to form a substation circuit, said impedance network including three coupled inductance elements, two of said elements being connected in series, one of said elements being arranged to be connected in shunt with said transmitter, said receiver being arranged to be connected in shunt with a second of said elements, whereby substantially no audio frequency voltage is developed across said receiver during operation of said transmitter, an auxiliary sound reproducing unit including an input circuit, and switching means for effectively disconnecting said receiver from said second inductance element and for coupling said input circuit to said second inductance element, whereby substantially no audio frequency voltage is developed across said input circuit during operation of said transmitter.

4. A telephone substation adapted to be connected to a telephone line for conversation over said line and comprising, in combination, a transmitter, a receiver and an anti-side tone impedance network arranged to be interconnected to form a substation circuit, said impedance network including three coupled inductance elements, two of said elements being connected in series, one of said elements being arranged to be connected in shunt with said transmitter, said receiver being arranged to be connected in shunt with a second of said elements, whereby substantially no audio frequency voltage is developed across said receiver during operation of said transmitter, an auxiliary sound reproducing unit including an amplifier and a loud speaker connected in tandem in the order named, said amplifier including an input circuit, and switching means for effectively disconnecting said receiver from said second inductance element and for coupling said input circuit to said second inductance element, whereby substantially no audio frequency voltage is developed across said input circuit during operation of said transmitter.

5. A telephone substation adapted to be connected to a telephone line for conversation thereover and comprising, in combination, a transmitter, a receiver, and an anti-side tone impedance network arranged to be interconnected to form a substation circuit, a member for supporting said receiver when not in use, switching means operative in response to the removal of said receiver from said supporting member for operatively including said receiver in said circuit, said anti-side tone impedance network being operative to prevent audio frequency energy generated by operation of said transmitter from being delivered to said receiver when said receiver is operatively included in said circuit, and an auxiliary sound reproducing unit, said switching means being operative to exclude said receiver from said circuit and operatively to include said auxiliary sound reproducing unit in said circuit when said receiver is supported by said supporting member, and said switching means, said network and said auxiliary sound reproducing unit being so connected and arranged that said network is operative to prevent audio frequency energy generated by operation of said transmitter from being delivered to said auxiliary sound reproducing unit when said auxiliary sound reproducing unit is operatively included in said circuit.

6. A telephone substation adapted to be connected to a telephone line for conversation there-over and comprising, in combination, a transmitter, a receiver, and an anti-side tone impedance network arranged to be interconnected to form a substation circuit said impedance net-work including three coupled inductance ele-
 5 ments, two of said elements being connected in series, one of said elements being arranged to
 10 be connected in shunt with said transmitter, a member for supporting said receiver when not in use, switching means operative in response to the removal of said receiver from said sup-
 15 porting member for connecting said receiver in shunt with a second of said elements, whereby substantially no audio frequency voltage is de-
 20 veloped across said receiver during operation of said transmitter, and an auxiliary sound re-
 25 producing unit including an input circuit, said switching means being operative effectively to disconnect said receiver from said second in-
 30 ductance element and to couple said input circuit to said second inductance element when said receiver is supported by said member, where-
 35 by substantially no audio frequency voltage is developed across said input circuit during op-
 40 eration of said transmitter when said input circuit is coupled to said second inductance ele-
 45 ment.
 40 7. A telephone substation adapted to be connected to a telephone line for conversation over said line and comprising, in combination, a transmitter, a receiver and an anti-side tone impedance network arranged to be interconnect-
 45 ed to form a substation circuit, said anti-side tone impedance network being operative to prevent audio frequency energy generated by operation of said transmitter from being delivered to said receiver, an auxiliary sound reproducing unit including an input circuit, switching means for substituting the input circuit of said aux-
 50 iliary sound reproducing device for said re-
 55 ceiver in said substation circuit, said switching means, said network and the input circuit of said sound reproducing unit being so connected and arranged that said network is operative to prevent audio frequency energy generated by the operation of said transmitter from being delivered to said input circuit when said input circuit is operatively included in said substation circuit, an impulsive device for transmitting im-
 60 pulses over said line and including a pair of normally open contacts, said contacts being ar-
 65 ranged to be closed during the operation of said device, and switching means for connecting said pair of contacts to short-circuit said receiver when said receiver is operatively included in said substation circuit and to short-circuit said input circuit when said input circuit is operatively included in said substation circuit.
 70 8. A telephone substation adapted to be connected to a telephone line for conversation over said line and comprising, in combination, a transmitter, a receiver and an anti-side tone impedance network arranged to be interconnected to form a substation circuit, said impedance net-work including three coupled inductance ele-
 75 ments, two of said elements being connected in series, one of said elements being arranged to be connected in shunt with said transmitter, said receiver being arranged to be connected in shunt with a second of said elements, whereby substantially no audio frequency voltage is developed across said receiver during operation of said transmitter, an auxiliary sound reproducing unit

including an input circuit, switching means for effectively disconnecting said receiver from said second inductance element and for coupling said input circuit to said second element, whereby substantially no audio frequency voltage is de-
 10 veloped across said input circuit during operation of said transmitter when said input circuit is operatively included in said circuit, an impulsive device for transmitting impulses over said line and including a pair of normally open contacts, said contacts being arranged to be closed during operation of said impulsive device, and switching means for connecting said contacts to short-
 15 circuit said receiver when said receiver is operatively included in said substation circuit and to short-circuit said input circuit when said input circuit is operatively included in said substation circuit. 5

9. A telephone substation adapted to be connected to a telephone line for conversation there-
 20 over and comprising, in combination, a trans-
 25 mitter, a receiver, and an anti-side tone im-
 30 pedance network arranged to be interconnected to form a substation circuit, a member for sup-
 35 porting said receiver when not in use, switching means operative in response to the removal of said receiver from said supporting member for operatively including said receiver in said circuit, said anti-side tone impedance network being op-
 40 erative to prevent audio frequency energy gen-
 45 erated by operation of said transmitter from being delivered to said receiver when said re-
 50 ceiver is operatively included in said circuit, an auxiliary sound reproducing unit, said switch-
 55 ing means being operative to exclude said re-
 60 ceiver from said circuit and operatively to in-
 65 clude said auxiliary sound reproducing unit in said circuit when said receiver is supported by said supporting member, said switching means, said network and said auxiliary sound repro-
 70 ducing unit being so connected and arranged that said network is operative to prevent audio frequency energy generated by operation of said transmitter from being delivered to said auxiliary sound reproducing unit when said auxiliary sound reproducing unit is operatively included in said circuit, and an impulsive device for trans-
 75 mitting impulses over said line, said impulsive device including a pair of normally open contacts arranged to be closed during operation of said device, said switching means including contacts for connecting said first-mentioned pair of contacts to short-circuit said receiver during op-
 80 eration of said impulsive device and when said receiver is operatively included in said substa-
 85 tion circuit and for connecting said first-men-
 90 tioned pair of contacts to short-circuit the input circuit to said auxiliary sound reproducing unit during operation of said impulsive device and when said auxiliary sound reproducing unit is operatively included in said substation circuit. 60

10. A telephone substation adapted to be connected to a telephone line for conversation there-over and comprising, in combination, a trans-
 10 transmitter, a receiver, and an anti-side tone impedance network arranged to be interconnected to form a substation circuit, said impedance net-work including three coupled inductance elements, two of said elements being connected in series, one of said elements being arranged to be connected in shunt with said transmitter, a member for supporting said receiver when not in use, switch-
 15 ing means operative in response to the removal of said receiver from said supporting member for connecting said receiver in shunt with a second of 70

- 5 said elements, whereby substantially no audio frequency voltage is developed across said receiver during operation of said transmitter, an auxiliary sound reproducing unit including an input circuit, said switching means being operative effectively to disconnect said receiver from said second inductance element and to couple said input circuit to said second inductance element when said receiver is supported by said member, whereby substantially no audio frequency voltage is developed across said input circuit during operation of said transmitter when said input circuit is coupled to said second inductance element, and an impulsing device for 10 transmitting impulses over said line, said impulsing device including a pair of normally open contacts arranged to be closed during operation of said device, said switching means including contacts for connecting said first-mentioned pair of contacts to short-circuit said receiver during operation of said device and when said receiver is removed from said supporting member and for connecting said first-mentioned pair of contacts to short-circuit the input circuit of said auxiliary 15 sound reproducing unit during operation of said impulsing device and when said receiver is supported by said member.
- 10 11. A telephone substation adapted to be connected to a telephone line for conversation over said line and comprising, in combination, a sound reproducing unit, an input circuit for said unit, an input transformer including a primary winding and a secondary winding, said secondary winding being included in said input circuit, an 15 impulsing device for transmitting impulses over said line, means for effectively short-circuiting said secondary winding during operation of said device, thereby to prevent said sound reproducing device from responding to current flowing 20 through said secondary winding during operation of said device, and means for at least partially short-circuiting said primary winding during the operation of said impulsing device.
- 20 12. A telephone substation adapted to be connected to a telephone line for conversation over said line and comprising, in combination, a sound reproducing unit, an input circuit for said unit, an input transformer including a primary winding and a secondary winding, said secondary winding being included in said input circuit, an 25 impulsing device for transmitting impulses over said line, a normally incomplete path for effectively short-circuiting said secondary winding for alternating or transient voltages developed thereacross, said path including a capacitance element, and means for completing said path during operation of said device, thereby to prevent said sound reproducing device from responding to alternating or transient voltages developed across 30 said secondary winding during operation of said device.
- 30 13. A telephone substation adapted to be connected to a telephone line for conversation over said line and comprising, in combination, a sound reproducing unit including a vacuum tube amplifier and a translating device connected in tandem in the order named, an input circuit for said amplifier, a voltage amplifying transformer comprising a primary winding and a secondary winding, said secondary winding being included in said input circuit, an 35 impulsing device for transmitting impulses over said line, a normally incomplete path for effectively short-circuiting said primary winding, thereby substantially to minimize the development of transient or alternating voltages across said secondary winding for alternating or transient voltages developed thereacross, said path including a capacitance element, means responsive to the operation of said impulsing device for completing said path thereby to prevent said sound reproducing means from responding to alternating or transient voltages developed across said secondary winding during operation of said 40 impulsing device, and means responsive to the operation of said impulsing device for at least partially short-circuiting said primary winding, thereby substantially to minimize the development of transient or alternating voltages across said secondary winding during operation of said 45 impulsing device.
- 40 14. A telephone substation adapted to be connected to a telephone line for conversation over said line and comprising, in combination, a sound reproducing unit including a vacuum tube amplifier and a translating device connected in tandem in the order named, an input circuit for said 45 amplifier, a voltage amplifying transformer comprising a primary winding and a secondary winding, said secondary winding being included in said input circuit, an impulsing device for transmitting impulses over said line, a normally incomplete path for effectively short-circuiting said 50 secondary winding for alternating or transient voltages developed thereacross, said path including a capacitance element, means responsive to the operation of said impulsing device for completing said path thereby to prevent said sound reproducing means from responding to alternating or transient voltages developed across said secondary winding during operation of said 55 impulsing device, and means responsive to the operation of said impulsing device for at least partially short-circuiting said primary winding, thereby substantially to minimize the development of transient or alternating voltages across said secondary winding during operation of said 60 impulsing device, and means responsive to the operation of said impulsing device for at least partially short-circuiting said primary winding, thereby substantially to minimize the development of transient or alternating voltages across said secondary winding during operation of said 65 impulsing device, switching means for connecting said substation to said line, and contacts included in said switching means for completing said path when said substation is disconnected from said line.
- 65 15. A telephone substation adapted to be connected to a telephone line for conversation over said line and comprising, in combination, a transmitter, a receiver and an anti-side tone impedance network arranged to be interconnected to form a substation circuit, a member for supporting said receiver when not in use, switching means operative in response to the removal of said receiver from said supporting member for operatively including said receiver in 70
- 70 16. A telephone substation adapted to be connected to a telephone line for conversation over said line and comprising, in combination, a transmitter, a receiver and an anti-side tone impedance network arranged to be interconnected to form a substation circuit, a member for supporting said receiver when not in use, switching means operative in response to the removal of said receiver from said supporting member for operatively including said receiver in 75

said circuit, said anti-side tone impedance network being operative to prevent audio frequency energy generated by operation of said transmitter from being delivered to said receiver when 5 said receiver is operatively included in said circuit, an auxiliary sound reproducing unit including a vacuum tube amplifier and a translating device connected in tandem in the order named, an input circuit for said amplifier, a voltage amplifying transformer including a primary winding and a secondary winding, said secondary winding being included in said input circuit, said switching means being operative to exclude said receiver from said substation circuit and operatively to include said primary winding in said 10 substation circuit when said receiver is supported by said supporting member, said switching means, said network and said primary winding being so connected and arranged that said net- 15 work is operative to prevent audio frequency energy developed by operation of said transmitter from being delivered to said input circuit when said primary winding is operatively included in said substation circuit, an impulsing device for transmitting impulses over said line, means responsive to operation of said impulsing device for short-circuiting said receiver when said receiver is operatively included in said substation circuit and for effectively short-circuiting 20 said primary winding when said primary winding is operatively included in said substation circuit, a normally incomplete path for effectively short-circuiting said secondary winding for transient or alternating voltages, said path including a capacitance element, means responsive to the operation of said impulsing device for completing said path, and contacts included in said switching means for completing said path when said receiver is removed from said supporting member. 25

17. A telephone substation adapted to be connected to a telephone line for conversation over said line and comprising, in combination, a transmitter, a receiver and an anti-side tone impedance network arranged to be interconnected to form a substation circuit, a member for supporting said receiver when not in use, switching means operative in response to the removal of said receiver from said supporting member for operatively including said receiver 30 in said circuit, said anti-side tone impedance network being operative to prevent audio frequency energy generated by the operation of said transmitter from being delivered to said receiver when said receiver is operatively included in said circuit, an auxiliary sound reproducing unit including a vacuum tube amplifier and a translating device connected in tandem in the order named, an input circuit for said amplifier, a voltage amplifying transformer including a primary winding and a secondary winding, said secondary winding being included in said input circuit, said switching means being operative to exclude said receiver from said substation circuit and operatively to include said primary winding 35 in said substation circuit when said receiver is supported by said supporting member, said switching means, said network and said primary winding being so connected and arranged that said network is operative to prevent audio frequency energy developed by operation of said transmitter from being delivered to said input circuit when said primary winding is operatively included in said substation circuit, an impulsing device for transmitting impulses over said line, means responsive to the operation of said im- 40

70

75

pulsing device for short-circuiting said receiver when said receiver is operatively included in said substation circuit and for effectively short-circuiting said primary winding when said primary winding is operatively included in said substation circuit, a normally incomplete path for effectively short-circuiting said secondary winding for transient or alternating voltages, said path including a capacitance element, means responsive to the operation of said impulsing device for completing said path, contacts included in said switching means for completing said path when said receiver is removed from said supporting member, switching means for connecting said substation to said line, and contacts included in said switching means for completing said path when said substation is disconnected from said line. 5

18. Telephone substation apparatus adapted to be connected to a telephone line for conversation thereover and comprising, in combination, transmitting means and receiving means adapted to be interconnected to form a substation circuit, said receiving means including an amplifier and a loud speaker connected in tandem in the order named, an input circuit for said amplifier, a receiver adapted to be used in lieu of said receiving means in communicating over said line, and means for effectively short-circuiting said amplifier input circuit when 30 said receiver is connected for use in communicating over said line. 35

19. Telephone substation apparatus adapted to be connected to a telephone line for conversation thereover and comprising, in combination, transmitting means and receiving means adapted to be interconnected to form a substation circuit, said receiving means including an amplifier and a loud speaker connected in tandem in the order named, an input circuit for said amplifier, a receiver, switching means operable selectively to connect said receiving means and said receiver for use in communicating over said line, and means including said switching means for effectively short-circuiting said amplifier input circuit when said receiver is connected for use in communicating over said line. 40 45

20. Telephone substation apparatus adapted to be connected to a telephone line for conversation thereover and comprising, in combination, transmitting means and receiving means adapted to be interconnected to form a substation circuit, said receiving means including an amplifier and a loud speaker connected in tandem in the order named, an input circuit for said amplifier, a receiver, a member for supporting said receiver when not in use, switching means operative in response to removal of said receiver from said supporting member, means including said switching means for selectively connecting said receiving means and said receiver for use in communicating over said line, and means including said switching means for rendering said amplifier input circuit ineffective to deliver alternating current energy to said receiving means. 50 55 60 65

21. Telephone substation apparatus adapted to be connected to a telephone line for conversation thereover and comprising, in combination, transmitting means and receiving means adapted to be interconnected to form a substation circuit, said receiving means including an amplifier and a loud speaker connected in tandem in the order named, an input circuit for said amplifier, a receiver, a member for supporting said receiver when not in use, switching means operative in 70 75

- response to removal of said receiver from said supporting member, means including said switching means for selectively connecting said receiving means and said receiver for use in communicating over said line, and means including said switching means for effectively short-circuiting said amplifier input circuit when said receiver is connected for use in communicating over said line.
22. A telephone substation adapted to be connected to a telephone line for conversation there-over and comprising, in combination, a transmitter, a receiver and an anti-side tone impedance network arranged to be interconnected to form a substation circuit, said anti-side tone impedance network being operative to prevent audio frequency energy generated by operation of said transmitter from being delivered to said receiver, an auxiliary sound reproducing unit including an amplifier and a loud speaker connected in tandem in the order named, an input circuit for said amplifier, switching means for substituting said input circuit for said receiver in said substation circuit, said network and the input circuit of said amplifier being so connected and arranged that said network is operative to prevent audio frequency energy generated by operation of said transmitter from being delivered to said input circuit when said input circuit is operatively included in said substation circuit, an impulsive device for transmitting impulses over said line, and means controlled by said impulsive device for preventing audio frequency energy from being delivered to said input circuit during operation of said device.
23. A telephone substation adapted to be connected to a telephone line for conversation there-over and comprising, in combination, a transmitter, a receiver and an anti-side tone impedance network arranged to be interconnected to form a substation circuit, said anti-side tone impedance network being operative to prevent audio frequency energy generated by operation of said

transmitter from being delivered to said receiver, an auxiliary sound reproducing unit including an amplifier and a loud speaker connected in tandem in the order named, an input circuit for said amplifier, switching means for substituting said input circuit for said receiver in said substation circuit, said network and the input circuit of said amplifier being so connected and arranged that said network is operative to prevent audio frequency energy generated by operation of said transmitter from being delivered to said input circuit when said input circuit is operatively included in said substation circuit, an impulsive device for transmitting impulses over said line, said device including contact springs adapted to be operated into engagement during operation of said device, and means comprising a path shunting said input circuit and completed in response to engagement of said contacts for preventing audio frequency energy from being delivered to said input circuit during operation of said device.

24. A telephone substation adapted to be connected to a telephone line for conversation over said line and comprising, in combination, a sound reproducing unit including an amplifier, an input circuit for said amplifier, switching means for connecting said substation to said line, and means controlled by said switching means for effectively short-circuiting said input circuit when said substation is disconnected from said line.

25. A telephone substation adapted to be connected to a telephone line for conversation over said line and comprising, in combination, a sound reproducing unit including an amplifier, an input circuit for said amplifier, switching means for connecting said substation to said line, and a low impedance path completed by contacts included in said switching means for effectively short-circuiting said input circuit when said substation is disconnected from said line.

JOHN HENRY VOSS.
